DFS. 2140

Franklin Timmons of Washington, D.C.

assignor to

William Miller, of Providence, R.I.

Letters Patent No. 2140. Dated July 18, 1865.

Design for a Medallion of Gen. Grant.

The schedule referred to in three Letters Patent and making part of the same.

To all whom it may concern:

Be it known, that Franklin Timmons, of the City of Washington, D.C. have originated and produced a new model of which the accompanying photograph is a true representation.

What I claim as my invention or production, and desire to secure by Letters Patent, is the design for Mezzo-relievo Medallion Portrait of Gen. Grant, represented by the photograph herewith attached.

W. H. French.

Edm' F. Brown.

Peter Baumgärtner.

Franklin Timmons.
